UNITED STATES PATENT OFFICE.

LANSON C. ROSS, OF KILLDEER, NORTH DAKOTA.

BRACING DEVICE.

Application filed February 28, 1922. Serial No. 539,969.

To all whom it may concern:

Be it known that I, LANSON C. Ross, a citizen of the United States, and resident of Killdeer, in the county of Dunn and State 5 of North Dakota, have invented certain new and useful Improvements in Bracing Devices, of which the following is a specification.

This invention relates to bracing devices 10 especially adapted for use on Ford automobiles.

Briefly stated an important object of this invention is to provide reliable means for bracing the front cross member of the frame 15 of a Ford car, which cross member usually breaks intermediate its ends as a result of an excessive strain.

Further the invention forming the subject matter of this application aims to provide a bracing device of the character specified in which the same is provided with simple means whereby it may be attached to a Ford car without substantially altering the construction of the vehicle or marring the 25 appearance of the same.

Also the improved bracing device forms a means for guarding the radiator.

A further object is to provide a bracing device of the character specified which is 30 of highly simplified construction, durable in use and cheap to manufacture.

Other objects and advantages of the invention will be apparent from the course of the following description.

35 In the drawing, wherein like numerals designate like parts throughout the same,

Figure 1 is a front elevation of the improved bracing device applied.

Figure 2 is an end elevation of the bracing device applied.

Figure 3 is a group perspective of the improved bracing device.

In the drawing wherein for the purpose of illustration is shown a preferred embodiment of the invention the numeral 5 designates the front cross member of the frame 45 6 of a motor vehicle, which in this case is a Ford. As illustrated in Figure 1 the front cross member 5 has its ends extended upwardly so as to provide a lower intermediate portion 7 which usually breaks as a result of strain or continued and excessive vibration.

The fender supporting arms 10 are arranged on opposite sides of the frame and 55 are secured to the same by means of fasten-

ing bolts 11 which extend through the attaching plates 12 of the arms. In carrying out the invention the brace is provided with a pair of brackets 14 adapted to be arranged 60 at opposite sides of the frame and connected to the bolts 11.

As illustrated in Figure 3 each bracket is formed from a single length of metal bent intermediate its ends as indicated at 16 to 65 provide inner and outer arms 17 and 18 respectively, the outer arm 17 having its forward portion apertured as indicated at 19 for the reception of a fastening bolt 11 whereby the outer arm 17 may be securely 70 and flatly engaged with the base plate 12.

The inner arm 18 of each bracket 14 has its terminal portion extended angularly to provide a lug 20 adapted to contact with the forward end of the frame whereby to 75 prevent the bracket from being bent inwardly whereby the tightening of the nut 24 threaded on the end of the truss rod 26.

In carrying out the invention a truss rod 26 is extended through aligned openings in 80 the arms 17 and 18 of the brackets and the nuts 24 are subsequently applied so as to brace the end portions of the cross member 5. This prevents the end portions of the 85 end member 5 from bending downwardly and breaking the cross member at the point 7.

With reference to the foregoing description taken in connection with the accompanying drawing it will be seen that the improved 90 brace may be conveniently applied to a motor vehicle without substantially altering the construction of the same and without in any way marring the appearance of the vehicle.

Further the truss rod 26 which extends in advance of the radiator effectively protects the radiator in the event of a collision. If desired the truss rod 26 may be used as a supporting means for a license plate.

With the reference to Figure 3 it will be observed that the bearing lug 20 of each bracket extends from the intermediate portion of the bracket and contacts with the front end of the frame so as to effectively 105 prevent bending of the bracket as a result of extreme tightening of the nut 24.

Having thus described the invention, what is claimed is:-

1. A bracing device for the front cross 110 member of a vehicle frame comprising a pair of brackets, each of which is formed

from a length of metal bent intermediate its ends to provide a pair of arms, one of the arms of each bracket being apertured for the reception of an attaching member by means 5 of which the brackets may be secured to the side of a vehicle frame, and the other arm being extended angularly to provide a bearing lug adapted to flatly contact with the front end of the vehicle frame whereby 10 to limit the inward movement of the bearings, and a rod extending through said pairs of arms and having fastening nuts mounted thereon, said bearing lugs being extended from the intermediate portions of the brack- 15 ets.

2. In combination with a vehicle frame having a cross member bent intermediate its ends, of a pair of brackets arranged at the ends of said cross member and each being formed from a length of metal bent intermediate its ends to provide inner and outer arms, the inner arms of the brackets being bent intermediate their ends to provide bearing lugs adapted to flatly contact with the forward end of the frame, the outer arms 20 of the brackets being secured to the frame, the outer portions of said arms being formed with aligned openings, and a tie rod extending through said openings. 25

LANSON C. ROSS.
